Patented June 7, 1921.

UNITED STATES PATENT OFFICE.

LLOYD G. KNOWLES, OF BEVERLY, MASSACHUSETTS, ASSIGNOR TO UNITED SHOE MACHINERY CORPORATION, OF PATERSON, NEW JERSEY, A CORPORATION OF NEW JERSEY.

GRINDING-MACHINE FOR BELT-KNIVES.

1,380,394.

Specification of Letters Patent.

Patented June 7, 1921.

Application filed August 22, 1919. Serial No. 319,154.

To all whom it may concern:

Be it known that I, LLOYD G. KNOWLES, a citizen of the United States, residing at Beverly, in the county of Essex and State 5 of Massachusetts, have invented certain Improvements in Grinding-Machines for Belt-Knives, of which the following description, in connection with the accompanying drawings, is a specification, like reference characters 10 on the drawings indicating like parts in the several figures.

This invention relates to machines for splitting sheet material such as leather. The invention is illustrated as embodied in 15 a machine of the type having an endless band or belt knife together with rolls which feed the work to and against the cutting edge of the knife. In such a machine it is essential, for best results, to maintain consistently 20 the closest possible relationship between the cutting edge of the knife and the bite of the feed rolls in order to split the leather uniformly. For the same reasons it is essential that the knife be kept uniformly 25 sharp. In machines of the character described it is customary to employ the upper run or stretch of the belt knife to split the material fed by the rolls and to provide one or more grinders to act on the lower run or 30 stretch of the belt, and to provide adjusting means to compensate for wear of the knife.

One of the objects of the present invention is to provide means for maintaining a 35 sharp and true cutting edge of the knife at the proper distance from the bite or nip of the rolls, with said edge uniformly beveled so that the line of cut will be in the proper plane relatively to the feed rolls.

An important feature of this invention, therefore, consists in novel mechanism including a pair of oppositely facing grinders having flat acting surfaces, and means for simultaneously adjusting both grinders toward the edge of the knife, whereby no change in shape of the cutting edge occurs as the grinding wheels wear.

Further features of the invention consist in means for adjusting the feed rolls simultaneously with and in the same direction as the flat-faced grinders, and in novel means for adjusting the relative angular positions of the grinders to vary the angle of bevel produced on the knife edge, and in novel

means for independently adjusting the 55 grinders relatively to the plane of travel of the knife to compensate for unequal wear of the two grinders.

A further feature of the invention consists in the provision of gaging means for 60 determining if, and how much, adjustment is needed to insure equal beveling of opposite surfaces of the knife edge. The above and other features of the invention, including certain details of construction and combinations of parts, will now be described 65 with reference to the accompanying drawings and pointed out in the claims.

In the drawings,

Figure 1 is a side elevation, partly broken 70 out and in section, of the essential parts of a belt knife splitting machine having my improvements;

Fig. 2 is a plan view of an adjustment 75 securing member;

Fig. 3 is a detail elevation looking from the right of Fig. 1.

So much of the rigid frame-work of a belt knife leather splitting machine as is necessary for present purposes is indicated 80 at 10. A special machine of the type referred to is illustrated in the application for belt knife splitting machine filed in the name of W. C. Baxter, Serial No. 307,093.

The upper and lower stretches of the belt 85 knife are indicated in section at 11 in Fig.

1. It is to be understood that in the present machine the belt knife is stationary so far as any adjustment is concerned. That is, it does not move forward or backward 90 from the position indicated in Fig. 1. The feed rolls 12, 13, however, are adjusted relatively to the knife, for the special purpose of compensating for wearing away of the knife. As will be presently understood, the 95 grinding mechanism and the feed rolls are simultaneously adjusted relatively to the edge of the knife 11.

The feed rolls have their bearings in a head 14 which is adjustable in suitable ways 100 15 of the frame 10. A bracket 16 depends from the head 14. A lug 17 rigidly connected with the head 14 and bracket 16 is internally threaded to receive one portion of a differentially threaded screw 18, the outer portion of which engages an internally threaded portion of a bracket 19 suitably secured, as by bolts 20, to the rigid

frame 10. Secured to the outer end of screw 18 is a ratchet wheel 21, a suitable hood 22 being provided to protect the member 21. By means of a handle 23 connected with a pawl 24 mounted in an oscillatory block 25, the ratchet wheel and the screw 18 can be manually operated as hereinafter described to adjust the head 14 and the feed rolls and the bracket 16 carrying the grinders, relatively to the upper and lower runs or stretches of the knife respectively.

The bracket 16 is formed or provided with segmental ways 26, 27 to which are fitted adjustable segmental plates 28, 29, each having slots 30 through which screws or bolts 31 pass into the ways 26, 27, binding nuts 32 being employed to hold the parts in position when adjusted. The ways 26, 27 are curved on the arcs of circles whose centers 20 coincide with the cutting edge of the knife 11.

The upper plate 28 is formed or provided with an internally threaded bearing or socket 33 supporting an externally threaded sleeve 34 the internal portion of which forms a bearing for a shaft 35 having a pulley 36 at its upper end and provided at its lower end with an externally threaded disk to which is fitted an internally threaded ring 37 to clamp the base of the upper ring or cup-shaped grinder 38 against said disk of the shaft 35.

The lower ring or cup-shaped grinder 39 which is located at one side of the grinder 38 along the lower stretch of the belt knife 11 is secured upon the flange 40 of a tubular shaft 41 by means of a clamp ring 42. Ball bearing mechanism 43 is located between the under surface of the flange 40 and the upper end of a sleeve bearing 44 which is externally threaded, and is internally smooth to provide a bearing for the tubular shaft 41. The threaded portion of the sleeve 44 engages an internally threaded aperture in a bearing or socket 45 carried by the adjustable plate 29. To facilitate longitudinal adjustment of the sleeve bearing 44 by rotating it in the socket 45, the upper end of said sleeve 44 is provided with an annular handle 46. A similar annular handle 47 is carried by the upper sleeve bearing 34. It will now be understood that by means of the handles 46, 47 the bearings or sleeves 44, 34 can be adjusted longitudinally so as to vary the positions of the grinders relatively to the lower and upper surfaces of the blade or knife 11. To hold the sleeve bearings in the positions to which they are adjusted, each of them is provided with suitable means such as a clamp nut 48. This clamp nut, as best illustrated in Fig. 2, may consist of a split ring reduced in thickness or weakened as at 49 so that the two halves may yield, the opposite side of the ring 65 being formed with ears 50 through which a

right and left hand screw 51 passes, said screw being provided with a handle 52. By moving the handle 52 in one direction, the clamp nut 48 will open sufficiently to enable the sleeve bearing to be rotatably adjusted 70 to raise or lower the grinder and then the clamp nut 48 may be actuated to lock the sleeve by movement of the handle 52 in the opposite direction. A similar clamp nut is provided for securing the upper grinder 75 after it has been lowered or raised by actuation of the annular handle 47.

The shaft 40 is tubular in order that dust and other particles may be removed readily from the grinding point by means of any 80 suction apparatus connected to the lower end of said shaft. Secured to the lower portion of the shaft 41 is a pulley 53 upon which a belt 54 is mounted, said belt passing over a pulley 55 carried by shaft 56, then over a 85 pulley 57 carried by shaft 58, around the pulley 36, then back over another pulley on shaft 58 and around another pulley on shaft 56 to and around a driving pulley 59 carried by a suitably driven shaft 60.

Gages 61, 62 pivotally supported at 63, 63 by the adjustable plates 29, 28, respectively, are provided with springs 64 normally holding them in position determined by a stop 65 one of which is provided for each gage. 95 Each gage has an indicating shoulder or edge 66 to coact with an indicating point 67 for a purpose hereinafter described.

The operation of the mechanism is as follows:—

In a belt knife splitting machine of the type for which the present invention is designed as an attachment, the cutting edge of the knife is intended to permanently occupy or travel relatively to the rolls in a vertical 105 plane indicated by the dotted line α , and the distance between this line and a vertical line drawn through the axes and the nip of the rolls 12, 13 is usually about $\frac{5}{32}$ of an inch, said distance being commonly known 110 as the "offset". The upper run of the knife co-operates with the feed rolls while the lower run is acted upon by the two grinders 38, 39 which are preferably cup-shaped and consequently have flat acting 115 surfaces. Said grinders are so mounted that their axes are slightly inclined to each other. As the knife wears away, the feed rolls are adjusted toward the knife by actuation of the screw 18, this adjustment also correspondingly shifting the grinders so that the point where the inclined edges of the grinders cross each other, said point being indicated at γ , will shift correspondingly with the shifting of the feed rolls. Consequently 120 when the feed rolls are adjusted toward the knife, the grinders are adjusted in the same direction an equal amount.

To vary the angle at which either grinder may operate upon the knife, the plate 28 or 130

29 may be adjusted by loosening the nuts 32 and then shifting the plates 28 and 29 to any desirable extent permitted by the slots 30 and then resetting the nuts 32.

5 I will now describe the utility and operation of the gages 61, 62. As these gages operate exactly alike, the operation of the gage 61 only will be described. The mounting and adjustment of the parts is such that 10 when the grinder 39 is properly located so that it will grind the knife to a point so that the cutting edge will be exactly in line with the mid thickness of the knife, rotation of the gage 61 upon its pivot 63 until the tip 15 of the gage 61 bears upon the edge of the grinder, will cause the indicating edge 66 of the gage to register with the point or indicator 67. If the edge 66 does not accurately register with the point 67 when the gage has 20 been swung as described, then the operator rotates the sleeve 44 (after loosening the nut 48) until the edge of the grinder 39 is in such position that when the tip of the gage 61 is in contact with said edge of the grinder, 25 then the gage edge 66 will register with the point 67. By this means the operator can at any time tell whether the grinders are in proper positions by manipulating the gages 61, 62.

30 When the grinders have been adjusted in their proper positions longitudinally and angularly, and the knife is to be sharpened, the operator effects fine adjustment of the grinders and feed rolls toward the knife by 35 operating the handle 23. Said handle is pivotally connected to the lower end of the stem 68 of pawl 24, and has a cam surface 69. A spring 70 mounted in block 25 tends to yieldingly hold the pawl 24 in engagement with the teeth of ratchet wheel 21. Fixed stops 71 limit the oscillation of block 40 25 which is hung upon the outer end of screw 18 by an arm or link 72. When the operator swings the block 25 by means of 45 handle 23 while the latter is in the position shown in Fig. 1, the pawl 24 effects a very gradual actuation of the screw 18 to whatever extent is necessary to bring the grinders into effective position to sharpen the knife. 50 The same operation causes the feed rolls to move to the same extent so that the nip or bite of the rolls will be at the proper distance from the edge of the upper run of the knife.

55 There are, of course, times when it is necessary to back off or separate the grinders and feed rolls from proximity to the knife, such as when a worn out belt-knife is to be replaced by a new one. To effect this, the 60 operator throws the handle 23 down to a vertical or pendant position which causes its cam portion 69 to so bear on the bottom of block 25 as to withdraw the pawl 24 from the ratchet wheel and leave the latter

free to be rotated by a suitable wrench 73 65 which is indicated only by dotted lines in Fig. 1 because it is not intended to leave said wrench permanently in place.

To aid in so adjusting the plates 28, 29, that the flat faces of the two grinders will 70 operate in corresponding angular planes on the opposite sides of the knife edge, the bracket 16 is provided with pins having indicating points 74 to coöperate with suitable scale marks carried by the plates 28, 29, the 75 latter having arc slots 75 through which the indicator pins project.

It will be readily understood that in the use of a machine of this character the operator would not be able to see any difference 80 in the length of the bevels on the opposite surfaces of the knife edge, unless such difference is excessive. Nor could he see that the edge of the knife is too far back from the bite or nip of the feed rolls. By employing 85 the pivoted gages 61, 62, he can inform himself as to either or both of the said questions merely by manipulating the gages in the manner described, and then effecting any necessary adjustment resulting from the use 90 of the gages.

Having described my invention, what I claim as new and desire to secure by Letters Patent of the United States is:

1. A grinding attachment for a belt knife 95 splitting machine, comprising a pair of oppositely facing flat-surfaced grinders, oppositely extending drive shafts for the grinders, and means for simultaneously adjusting both grinders toward the cutting 100 edge of the knife.

2. In a machine of the character described, in combination, a belt knife, rolls for feeding work to the knife, flat-faced grinders for operating upon the knife, and means for 105 simultaneously adjusting the feed rolls and the grinders relatively to the cutting edge of the knife.

3. In a machine of the character described, in combination, a belt knife, rolls for feeding work to one stretch of the knife, flat-faced grinders for operating upon the other stretch of the knife, and means for simultaneously adjusting the feed rolls and the 110 grinders relatively to those portions of the 115 knife with which they coöperate.

4. In a machine of the class described, in combination, a belt knife, a pair of rotary flat-faced grinders, drive shafts for the grinders having their axes slightly inclined 120 relatively to each other and to the knife, and means for simultaneously adjusting the grinders toward the edge of the knife without altering their angular relationship.

5. In a machine of the character described, 125 in combination, a belt knife, a pair of rotary flat-faced grinders having their axes slightly inclined relatively to each other and

to the knife, oppositely extending drive shafts for the grinders, and means for adjusting the angular relationship of said grinders.

5 6. In a machine of the character described, in combination, a belt knife, a pair or rotary flat-faced grinders, having their axes slightly inclined relatively to each other and to the knife, means for adjusting 10 said grinders longitudinally of their axes of rotation, and means for adjusting the grinders in arcs of circles whose centers coincide with the cutting edge of the knife.

7. In a machine of the class described, in 15 combination, a belt knife, a grinder for the cutting edge of the knife, means for adjusting the grinder relatively to the knife, and a finger for engaging the working surface of the grinder for indicating the amount of 20 adjustment necessary to effect proper action of the grinder upon the knife.

8. In a machine of the character described, in combination, a belt knife, a pair of rotary flat-faced grinders having their axes slightly 25 inclined relatively to each other and to the knife, means for adjusting said grinders longitudinally of their axes of rotation, and gage devices including fingers for engaging the grinders to insure equal bevels on the 30 knife by indicating the amount of adjustment necessary to effect proper action of the grinders upon the knife.

9. In a machine of the character described, in combination, a belt knife, a pair 35 of flat-faced grinders mounted to equally bevel opposite surfaces of the knife, and means for adjusting the grinders in arcs of circles whose centers coincide with the meeting line of the two bevels.

40 10. In a machine of the character described, in combination, a belt knife, a pair of flat-faced grinders mounted to equally bevel opposite surfaces of the knife, means for adjusting the grinders in arcs of 45 circles whose centers coincide with the meeting point of the two bevels, and gage devices for determining if the grinders are in accurate positions relatively to said point.

11. In a machine of the character described, in combination, a belt knife, a head 50 carrying rolls for feeding work to the knife, a bracket connected with said head, means for simultaneously adjusting the head and bracket relatively to the plane of operation 55 of the knife, curvilinearly adjustable plates

carried by said bracket, and flat-faced grinders rotatively mounted in said plates.

12. In a machine of the character described, in combination, a belt knife, a head carrying rolls for feeding work to the knife, 60 a bracket connected with said head, means for simultaneously adjusting the head and bracket relatively to the plane of operation of the knife, curvilinearly adjustable plates carried by said bracket, grinders rotatably 65 mounted in said plates and means for adjusting said grinders longitudinally of their axes of rotation.

13. In a machine of the character described, in combination, a belt knife, and a 70 pair of rotary flat-faced grinders having their axes inclined relatively to each other, one of said grinders having a tubular shaft for the escape of fine material removed from the knife by the grinders. 75

14. In a machine of the character described, in combination, a belt knife, a supporting member having an opening for the passage of one run of the knife, said supporting member having curved ways, bearing members adjustable along said ways, and a pair of rotary flat faced grinders having their shafts mounted in said bearing members. 80

15. In a machine of the character described, in combination, a belt knife, a pair of oppositely facing flat faced grinders mounted to act on opposite surfaces of one run of the belt knife, means for longitudinally adjusting the grinders, and a pair of 90 gages for determining the plane of operation of the acting faces of the grinders. 85

16. In a machine of the character described, in combination, a belt knife, a pair of oppositely facing flat faced grinders 95 mounted to act on opposite surfaces of one run of the belt knife, means for longitudinally adjusting the grinders, a pair of pivoted fingers adapted to be manually operated to contact with the faces of the grinders, 100 springs for normally holding said fingers in inoperative positions, and scales to coöperate with said fingers when the latter are manually operated to determine the amount of adjustment necessary to effect proper 105 action of the grinders upon the knife.

In testimony whereof I have signed my name to this specification.

LLOYD G. KNOWLES.
